(57) **CLAIM**

The ornamental design for a pivot work-light with hook, as shown and described.

DESCRIPTION

FIG. 1 is a perspective view of a pivot work-light with hook in a closed position, showing my new design.

FIG. 2 is a front view of the pivot work-light with hook in the closed position of FIG. 1;

FIG. 3 is a back view of the pivot work-light with hook in the closed position of FIG. 1;

FIG. 4 is a right-side view of the pivot work-light with hook in the closed position of FIG. 1;

FIG. 5 is a left-side view of the pivot work-light with hook in the closed position of FIG. 1;

FIG. 6 is a top view of the pivot work-light with hook in the closed position of FIG. 1;

FIG. 7 is a bottom view of the pivot work-light with hook in the closed position of FIG. 1;

FIG. 8 is a perspective view of the pivot work-light with hook of FIG. 1 in an open position;

FIG. 9 is a front view of the pivot work-light with hook in the open position of FIG. 8;

FIG. 10 is a right-side view of the pivot work-light with hook in the open position of FIG. 8; and,

FIG. 11 is a bottom view of the pivot work-light with hook in the open position of FIG. 8.
